UNITED STATES PATENT OFFICE.

GRACE E. WHITCOMB, OF ANDOVER, AND JAMES E. BARNARD, OF FRANKLIN,
NEW HAMPSHIRE.

DESIGN FOR A COMBINED FORK AND SPOON.

SPECIFICATION forming part of Design No. 30,129, dated February 7, 1899.

Application filed December 24, 1898. Serial No. 700,288. Term of patent 7 years.

To all whom it may concern:

Be it known that we, GRACE E. WHITCOMB, residing at Andover, and JAMES E. BARNARD, residing at Franklin, in the county of Merrimac and State of New Hampshire, citizens of the United States, have invented and produced a new and original Design for a Combined Fork and Spoon, of which the following is a specification, reference being had to the accompanying drawings, forming a part thereof.

Figure 1 is a view looking into the bowl of the spoon and at the back of the fork, showing our new design; and Fig. 2, an edge view thereof.

As shown in the drawings, the leading or material feature of our design consists of a straight handle, when viewed edgewise, having a fork upon one end turned in one direction and a spoon upon the other end turned in the reverse direction, A representing the handle, B the fork, and C the bowl of the spoon.

Our design when viewed in elevation, as in Fig. 1, shows the connecting-handle to be enlarged at its center, gradually tapering both toward the fork and the spoon, and having ornamentation upon the surface thereof.

By thus arranging a fork and spoon upon the same handle and reversely each is in the proper position for use and the opposite member may serve as a portion of the handle.

Having thus described our invention, what we claim as new is—

The design for a combined fork and spoon substantially as herein shown and described.

In testimony whereof we have hereunto affixed our signatures in the presence of two subscribing witnesses.

GRACE E. WHITCOMB.
JAMES E. BARNARD.
